UNITED STATES PATENT OFFICE

129,231

DESIGN FOR A DRESS ENSEMBLE

Margaret Hobgood, New York, N. Y.

Application August 2, 1941, Serial No. 102,642

Term of patent 3½ years

To all whom it may concern:

Be it known that I, Margaret Hobgood, a citizen of the United States of America, residing in New York city, county of New York and State of New York, have invented a new, original, and ornamental Design for a Dress Ensemble, of which the following is a specification, reference being had to the accompanying drawing, forming part thereof.

Fig. 1 is a front view of a dress ensemble showing my new design.

Fig. 2 is a rear view thereof.

Fig. 3 is a fragmentary front view of the dress member.

Fig. 4 is a rear view of Figure 3.

I claim:

The ornamental design for a dress ensemble, substantially as shown.

MARGARET HOBGOOD.
